UNITED STATES PATENT OFFICE.

WILLIS L. HOUGH, OF LACONIA, NEW HAMPSHIRE.

PARTIAL DENTURE AND REMOVABLE BRIDGE.

1,128,876.

Specification of Letters Patent. Patented Feb. 16, 1915.

Application filed March 6, 1914. Serial No. 822,960.

To all whom it may concern:

Be it known that I, WILLIS L. HOUGH, of Laconia, in the county of Belknap and State of New Hampshire, have invented certain new and useful Improvements in Partial Dentures and Removable Bridges, of which the following is a specification.

This invention relates to dentistry, especially of the character known as removable bridgework or partial dentures.

One of the objects of my present invention is to provide an improved coupling or connection to enable partial dentures or bridges to be removed or replaced without requiring the services of a dentist.

Another object is to provide an improved coupling of this character which may be tightened or adjusted by the patient without going to the dentist.

Another object is to provide an improved coupling or connection, the member which is carried by the plate or bridge to be removed, being so constructed that it can be easily removed from the rubber material of the plate by heating, and then a new one easily re-connected with the rubber material without requiring re-vulcanization of the plate.

Another object is to provide an improved device of the character described which will allow for settling of the plate to place, as the mucous membrane or the gums yield.

To these ends the invention consists in the improvements which I shall now proceed to describe and claim.

Of the accompanying drawings in which I have merely illustrated one embodiment of my invention:—Figure 1 is a plan view illustrating bridgework adapted for connection with the lower jaw of a patient which retains eight natural teeth; Figs. 2 and 3 are perspective views of portions of the structure illustrated in Fig. 1, on a larger scale; and Fig. 4 is a perspective view of the female member of the coupling or connection, considerably enlarged.

The same reference characters represent the same parts in all of the views.

12 and 12^a indicate two plates or base members which may be made of the usual kind of rubber material employed in this work, said plates carrying artificial molars, the two plates being connected by a bar or wire extending across on the lingual side of

eight natural teeth of the patient. The two end teeth of the series of natural ones are indicated at 14 and 14^a.

The female member of the coupling which is adapted to be soldered to a gold crown of the natural tooth 14 or 14^a, comprises a back plate 15 bent to form flanges 16 between which and the back plate are recesses 17. This member is so formed, as clearly illustrated in Fig. 4, as to present a tapering socket including the recesses 17, and a tapering passageway between the edges of the flanges 16. The other member of the coupling comprises a loop 18 of wire which is substantially pear-shaped, the portions of the wire which constitute the ends of the loop being bent as at 19, and the two ends of the wire presenting substantially parallel shank portions 20 adapted to be embedded in the plate 12 or 12^a, as clearly shown in Fig. 3. The shape of the loop 18 is such that its outer sides taper to correspond with the tapering formation of the socket of the female member.

When the plates 12, 12^a, with the artificial teeth carried thereby are to be connected with the natural teeth 14, 14^a, the two members 18 are engaged with the female members by a sliding movement, the contracted portions of the loops being pushed downwardly into the tapering recesses of the female members until the tapering sides of the loop bind into the recesses 17. During this movement the sides of the angular portions 19 slide down between the edges of the flanges 16. Preferably the two parts of the coupling are so proportioned that the sides of the portions 19 will bind in the narrower portion of the slot or passageway between the two flanges 16, 16 simultaneously with the binding of the wider portions of the loop 18 between the walls of the recesses 17. Of course, a reverse movement will readily separate the plates from the natural teeth 14, 14^a.

The fact that the loop 18 is capable of slight yielding or contraction, enables the plate or plates to settle to place, as the mucous membrane or gums yield.

When it is necessary to re-place the male member of the coupling with a new one, said member being the one which wears the quickest, the straight wire shanks 20, which anchor said member in the plate, may be

easily removed from the rubber material by heating the wire sufficiently to soften the rubber so that the said member can be pulled out. Then by heating a new one, 5 and rubbing it over some gutta percha, the shanks of the new one can be secured in the recess from which the former one was removed. I do not, of course, limit myself to this particular way of substituting a new 10 member for a worn one, since the new one may be cemented in position if desired. In either case, however, no re-vulcanizing of the plate is necessary.

Owing to the fact that the connection of 15 the members with each other is effected by a wedging action, the plate, or plates, or denture, can be easily removed or re-placed, and when in place held very tightly and still with some possibility of the plate or 20 plates following any recession of the gums.

Adjustment to overcome looseness due to wear or other causes can be readily effected by the patient, without the services of a dentist, by simply inserting a knife or other 25 suitable instrument in the loop 18 and prying the sides thereof apart sufficiently to

insure a tight connection when the two members are coupled together.

Obviously the coupling may be applied to other forms of dentures or bridgework than 30 illustrated, according to the needs of the patient, and the number and kind of artificial teeth will be according to such needs.

Having now described my invention what 35 I claim is:—

Devices for separably connecting dentures or bridgework, comprising two members one of which has a back portion to be attached to a natural tooth and a slotted front and a beveled recess between said back and 40 front, the other member consisting of a loop of wire with its free ends substantially parallel to each other and at an angle to the loop, the loop being adapted to be expanded 45 to increase its width.

In testimony whereof I have affixed my signature, in presence of two witnesses.

WILLIS L. HOUGH.
